UNITED STATES PATENT OFFICE

2,573,749

MACHINE GUN AMMUNITION FEED

Phillip R. Wheeler, Alexandria, Va., Lee Morgan,
United States Navy, and Frederick C. Schoen-
ing, Alexandria, Va.

Application April 3, 1945, Serial No. 586,429

11 Claims. (Cl. 89—33)

(Granted under the act of March 3, 1883, as
amended April 30, 1928; 370 O. G. 757)

1

The invention relates to improvements in machine gun ammunition supply and feed apparatus and has for an object the provision of means for readily positioning a supply of ammunition in association with a machine gun and for effectively guiding and feeding the ammunition to the machine gun.

Another object is to provide a feed chute or feedway assembly which is of simple and easily assembled construction and which is adapted to be fixedly mounted upon the gun cradle structure.

A further object is the provision of mounting means on the gun cradle structure in association with the feedway assembly for removably supporting an ammunition box.

Another object is to provide a novel and effective latch mechanism providing for rapid positioning and removal of the ammunition box.

A further object is to provide means for quick loading of machine guns, such as the Browning type of machine guns, without the necessity of handling the ammunition belt, nor of opening the cover of the gun in order to place the loaded belt properly into the belt opening of the gun.

A still further object is to provide means mounting the ammunition box in a substantially balanced position substantially half above and half below the elevation trunnions or the center line of the gun to provide substantial equilibrium of the structure rotatably supported on the elevation trunnions in various angles of elevation.

Another object is to provide means whereby the feedway assembly is adjustable by reversal of a portion thereof for use for either right or left hand feed of the guns.

Another object is to provide a common supporting means for the feedway assembly and the ammunition box, and to provide such a support which is adapted to be removably fixed to either side of the gun cradle for either right or left hand feed.

Other objects and advantages of the present invention which contribute to the provision of an effective, efficient ammunition supply and feedway mounting for machine guns, will be apparent from the following more detailed disclosure having reference to the drawings thereof which are exemplary, and in which:

Fig. 1 is a side elevation of the apparatus assembled with the machine gun and associated structure.

Fig. 2 is a front elevation of the same.

Fig. 3 is a vertical cross-section on line 3—3 of Fig. 9, partly in elevation, of the ammunition

2

box and its mount and the feedway assembly and the common support therefor.

Fig. 4 is a perspective view of the ammunition box supporting bracket.

Fig. 5 is a sectional view substantially on the line 5—5 of Fig. 3.

Fig. 6 is a fragmentary detail plan view of the ammunition retaining pawl assembly.

Fig. 7 is a plan view of the feedway assembly.

Fig. 8 is a detail side elevation of the feedway assembly.

Fig. 9 is an elevation of the feedway assembly with the support plate shown in phantom.

Referring to the drawings, an ammunition container or box 1 is provided, containing a supply of ammunition preferably in the form of a metallic link belt of cartridges 2. The box is mounted on a bracket 47 which is secured by bolt means 6 to a support plate 66, and which in turn is bolted to the lugs 9a of the gun cradle 9 at 67, 68, 69, and 70, the support plate being provided with holes at these points for the purpose. The belt of cartridges discharges from a lateral opening 4 near the top of the box, into the mouth 5 of the feed chute 3, which cooperates with the feed opening 7 of the machine gun 8.

The feed chute 3 is also mounted upon the support plate 66 which is secured to the gun cradle 9, with the discharge end 10 of the feed chute in operative position to discharge into the feed opening of the gun 8. A desirable fixed mounting of the feed chute upon the support plate 66 which is fixed to the gun cradle, consists in the flanges 11 on the feed chute or feedway assembly 3 having openings 12 therein for alignment with corresponding openings 13 in the support plate 66 with securing means such as bolts 14 in said aligned openings.

A sprocket or star wheel assembly is mounted in bearings 15 in the upper part of the feed chute assembly 3 and comprises an axle 16 received in said bearings 15 and a sprocket or star wheel member 17 receiving said axle and secured on said axle by pin means 18 or the like. The pin means 18 may desirably be held in place by a removable clamping means 19 having resilient fingers 20 which clamp around the central portion of the star wheel member. The sprocket or star wheel member 17 preferably is provided with spaced apart sprocket or star wheels 21, one of larger diameter than the other for receiving and moving the belted cartridges of the ammunition supply from the exit opening 4 of the ammunition box 1 into the entrance opening 5 of the feed chute 3 as the sprocket member 17 is rotated.

The axle 16 of the sprocket assembly is provided with a handle or crank 22 for rotating it.

The feed chute or feedway assembly preferably comprises a main feed chute member 3 embodying the bearings 15 for the sprocket assembly, and the flanges 11 for mounting upon the support plate 66 secured to the gun cradle, and a feed chute cover member 3a pinned to the apertured ears 23 of the main feed chute member 3 by means of a pin 24 extending through the upper end of the cover member 3a and through the apertures of said ears, and held in place by cotter keys 25 in the ends of the pin. Lateral projections 26 of the cover are slidably received in slots 27 provided in the side members 28 of the main feed chute member 3.

At the lower end of the feed chute cover there is provided a roller assembly comprising a roller receiving recess 29 in the lower end of the feed chute cover 3a between arm members 30 having openings 31 therein receiving the roller shaft 32. The roller shaft is secured in the feed chute cover by pins 33 extending through the arm members 30 and through the roller shaft. The roller 34 may desirably be of metal or other suitable material and is rotatively mounted on the roller shaft 32 so as to be capable of sliding axially thereon. Bumpers 35 are provided on the roller shaft within the opposite arm members 30 of the feed chute cover 3a on either side of the roller 34 and normally spaced from said roller, being preferably of rubber or like resilient material. The roller can slide axially on the shaft as the belt of cartridges moves with the recoil motion of the gun, and the axial movement of the roller is limited and cushioned by the rubber stops or bumpers.

At the lower end of the feed chute, resilient fingers 36 are provided at either side thereof projecting partly into the feed opening 7 of the gun to guide the cartridges into the gun. The resilient fingers permit the belt of cartridges to move with the recoil and counterrecoil motion of the gun during firing. The resilient fingers or guide blades 36 may desirably be of spring metal. They are preferably curved to conform to the feed chute and extend from a point of attachment in the upper portion of the feedway assembly and may desirably be secured at their upper ends to the main feed chute member. The upper ends 37 of the fingers or guide blades are turned over and receive pins 38 passing therethrough and seated in outwardly extending apertured ears 39 of the main feed chute member 3, openings 40 being provided in the sides of the said member for receiving the turned over ends 37 of the guide blades or fingers.

Liners 41 and 42 of suitable material such as spring steel are secured within the main feed chute member and the cover, by means of rivets 43 or the like. The liner 42 for the cover is provided with a turned over part 44 which embraces the upper edge of the cover and is riveted through.

The gun feed opening 7 is provided with a feed pawl 46 and a retaining pawl 45.

At the upper ends of the side walls of the ammunition box bracket 47 notches 48 are provided for receiving lugs or pins 49 projecting from the sides 50 of the ammunition box for supporting the box in the bracket between the side walls 51 of the bracket.

At the lower end of the bracket, arms 52 are provided extending downwardly and outwardly at an angle to the vertical plane of the bracket. The bracket arms at their outer ends are each

provided with an inturned lip 53, providing surfaces inclining inwardly and downwardly for sliding reception of correspondingly inclined projections 54 on the opposite sides 50 of the ammunition box. The inclined lips 53 on the bracket arms constitute retaining means for the box requiring the box to be lifted for removal from the bracket.

The bracket 47 is provided with a latch 55 for retaining the box in position in the bracket, the latch being pivotally mounted to the side of the bracket and comprising a detent portion 56 below the pivot 57 for engagement with the upper surface 58 of the projection 54 on the side of the ammunition box to retain the box in position in the bracket by preventing its being lifted out of connection with the bracket. Spring means 59 are provided between the side wall of the bracket and the upper part 60 of the pivoted latch for urging the latch into box retaining position. The latch is pivoted at the inside of the side wall of the bracket and is desirably provided with an operating handle portion 61 or finger piece in the form of a bent extension embracing the front edge 62 of the side wall of the bracket and providing a stop properly positioning the latch in operative position and limiting its movement under the spring action. The latch 55 is released by moving the upper part 60 thereof outwardly against the spring action which swings the lower or detent portion 56 inwardly away from the projection 54 on the side of the box, so that the box may be removed from the bracket by lifting the box upwardly.

The inner wall of the ammunition box is shaped inwardly of the box providing a recess 63 to enable the wall of the box to clear portions of the feedway assembly, and the upper edge of the said inner wall of the box is bent over upon itself to form the lower wall 64 of the lateral opening 4 at the top of the box constituting the cartridge exit. A spring-pressed retaining pawl 65 is provided in the top of the ammunition box for engaging the cartridges in the exit opening of the box and preventing the ammunition belt from slipping back into the box when the belt is not engaged and retained by the belt holding or retaining pawl 45 on the gun. The pawl 65 yields upwardly about its pivot in feeding movement of the belt but retains the cartridge belt against retraction into the box.

The special latch mechanism permits rapid positioning and removal of the ammunition box. When the box is latched into position, the exit opening is in operative communication with the feed chute entrance opening.

The ammunition box and its supporting bracket are so disposed that the box is mounted in a balanced position on the gun substantially half above and half below the center of the elevation trunnions substantially on the center line of the gun, to provide substantial equilibrium of the structure rotatably supported on the elevation trunnions in various angles of elevation.

The advantage of mounting of the feed chute or feedway assembly upon the gun cradle structure instead of making it a part of the ammunition box is that the cost of the ammunition box is lowered, and since there must be numerous ammunition boxes or magazines for each gun, fewer feed chutes or feedway assemblies are needed.

The feedway mechanism is adapted to be adjusted for either right or left hand feed guns, for example, in the case of twin guns, depend-

ing upon which side of the cradle structure it is attached. The feed sprocket must be so positioned that the larger diameter sprocket wheel is towards the gun muzzle. The sprocket member therefore is reversed in the feed chute or feed-way assembly in order to adapt the feed chute to be changed from the right to the left side of the cradle structure or vice versa. The reversal of the feed sprocket or star wheel member is accomplished by simply removing the pin which holds the star wheel or sprocket member on its axle, removing the axle, reversing the sprocket member end for end and reinserting the axle. The axle may be reversed, if desired.

The vertically disposed supporting plate 66 which is bolted to the lugs 9a of the gun cradle, and to which the feed chute assembly and the ammunition box bracket are secured to be supported by said plate, is interchangeable or transferable in that it is adapted to be applied and attached to the lugs 9a at either side of the gun cradle as is indicated in phantom in Fig. 2.

The ammunition boxes are supplied as needed in filled condition, being differently loaded and marked for right and left hand feed, so that the cartridges in the ammunition belt within the boxes are pointed in the proper direction for right or left hand feed.

The apparatus permits quick loading of machine guns, because it does away with the necessity for handling the ammunition from the ammunition box and inserting it properly through the feed opening of the gun. It avoids the necessity of opening the cover of the gun. The machine gun apparatus of the present invention is particularly suitable for anti-aircraft use where the time element is of great importance, while not being limited to such use.

In the operation of the apparatus, the box is loaded with the ammunition belt, with the first cartridge in the belt held in the cartridge exit of the box by the spring pressed pawl. When the box is latched into position, the first cartridge is in contact with the star wheel or sprocket member, and rotation of the hand crank advances the belt down into the feed chute, under the lower roller, and past the feed and holding pawls of the gun. The gun is charged twice and is then ready to fire.

The gun cradle is mounted on the carriage yoke 10a which in turn is supported by the stand 11. Hose for cooling fluid is indicated at 12. The elevation trunnion is indicated at 13.

Although but one embodiment of the invention is herein shown and described, it will be understood that various changes in the size, shape, and arrangement of parts may be made without departing from the spirit of the invention and it is not intended to limit the invention other than by the terms of the appended claims.

The invention described herein may be manufactured and used by or for the Government of the United States of America for governmental purposes without the payment of any royalties thereon or therefor.

What is claimed is:

1. In combination, a machine gun having a cartridge feed opening and a gun cradle structure, said gun cradle structure having horizontally disposed elevation trunnions, a cartridge feed chute fixedly mounted upon said gun cradle structure in communication with said cartridge feed opening and extending upwardly and outwardly therefrom and having a laterally disposed inlet opening at its upper end for communication with an

ammunition container to provide a substantially balanced assembly in respect to said elevation trunnions, said feed chute comprising a main feed chute member having apertured flanges bolted to the gun cradle structure, a sprocket member having spaced apart sprocket wheels and an axial bore, an axle in said bore and having a crank handle for rotating said sprocket member, means pinning said sprocket member to said axle, retaining means for the pin means, bearings in said main feed chute member supporting said axle and sprocket member beneath and in cooperative relation with said inlet opening to feed cartridges thereinto, resilient guide members having overturned upper ends passed through openings in the sides of said main feed chute member, apertured ears on said feed chute member, and pins in said ears and in said overturned ends of the resilient guide members, said guide members extending along said feed chute to the cartridge feed opening of the gun, a feed chute cover having side portions received in slots in the main feed chute member and means securing the cover to said member at the upper ends thereof, a roller shaft and roller thereon mounted in the lower end of the feed chute cover over the exit opening of the chute, said roller being capable of axial movement on said shaft and resilient buffers at either side of said roller and normally spaced therefrom and limiting said axial movement of the roller.

2. Apparatus according to claim 1 in which one of said spaced apart sprocket wheels is larger than the other, said retaining means for the sprocket pin means comprising a clamp engaging the pin means and having resilient fingers which clamp on the central portion of the sprocket member, said apparatus being adjustable in that the retaining means and sprocket pin means and axle are removable, and the sprocket member is reversible, for either right or left hand feed of the guns.

3. In combination with a machine gun having a cartridge feed opening, a gun cradle, said gun cradle having horizontally disposed elevation trunnions, a vertically disposed support plate mounted on said gun cradle at the side thereof, an ammunition belt container mounted on one side of said vertical support plate and disposed in a balanced position in respect to the center line of the elevation trunnions of the cradle, and a cartridge feed chute mounted on the opposite side of said vertical support plate from said ammunition belt container, said feed chute being disposed in communication with said feed opening of the gun and extending upwardly therefrom and having an inlet opening, a feed sprocket mounted in the said inlet opening, the feed sprocket being disposed in engagement with the ammunition belt with the ammunition container in place on its mount, and disposed to feed the ammunition belt into the feed chute and gun, said ammunition container having an outlet opening at its upper end in communication with said inlet opening of the feed chute, said vertically disposed support plate providing a common support for said feed chute and said ammunition box disposed on opposite sides of said vertical plate.

4. In apparatus according to claim 3, said vertically disposed support plate and said cradle having conforming surfaces thereon rendering said vertical support plate interchangeable or transferable in that it is adapted to be applied

and secured to either side of the gun cradle for either right or left hand feed of the gun.

5. In combination with a machine gun having a cartridge feed opening and a gun cradle structure, a cartridge feed chute mounted on said gun cradle structure in communication with said cartridge feed opening and extending upwardly therefrom and having an inlet opening, an ammunition belt container supporting bracket mounted on said gun cradle structure and disposed adjacent to said feed chute, an ammunition belt container, means removably mounting said ammunition container on said supporting bracket, the upper portion of said container having a lateral discharge opening therein disposed in operative communication with said inlet opening of the feed chute, a sprocket mounted in the cartridge feed chute at the inlet opening thereof, an external crank attached to the sprocket, and means in the ammunition container for holding the ammunition belt so that a cartridge in the belt is engaged by the sprocket with the ammunition container in place on its supporting bracket.

6. In combination with a machine gun having a cartridge feed opening and a gun cradle structure, a cartridge feed chute mounted upon said gun cradle structure in communication with said cartridge feed opening, an ammunition container supporting bracket mounted on the gun cradle structure, an ammunition container, means removably mounting said ammunition container on said supporting bracket comprising projecting members on said ammunition container, and co-operating surfaces on said bracket removably receiving said projecting members of said container, and a spring pressed pivoted latch on said supporting bracket for manually detachable engagement with a projecting member of the container to detachably retain the container in position on said bracket, and a sprocket wheel mounted in the cartridge feed chute and disposed in engagement with a cartridge in the ammunition container with the container in place on its supporting bracket.

7. In combination with a machine gun having a cartridge feed opening and a gun cradle, a vertically disposed support plate secured to said gun cradle at the side thereof, an ammunition feed chute fixedly mounted upon said support plate and disposed in communication with the ammunition feed opening of the gun and having an inlet opening, an ammunition container supporting bracket mounted on said support plate, an ammunition container having an outlet opening, means removably mounting said ammunition container on said supporting bracket with its outlet opening in operative communication with the inlet opening of said feed chute adjacent its inlet opening, an ammunition feed sprocket mounted in the said feed chute, the said vertically disposed support plate providing a common support for said feed chute and said ammunition box bracket, said vertically disposed support plate and said cradle having conforming surfaces thereon rendering said vertical support plate interchangeable or transferable in that it is constructed to be applied and secured to either side of the gun cradle for either right or left hand feed of the gun.

8. In combination with a machine gun having an ammunition feed opening, a feed pawl, a supporting cradle for the gun, and an ammunition feed chute mounted on the supporting cradle and adapted to feed the ammunition from a con-

tainer into the gun feed opening, a feed sprocket mounted at the inlet end of said feed chute, the feed chute being mounted symmetrically except for its feed sprocket in relation to a central plane 5 normal to the axis of the feed sprocket so that the feed chute can be used on either side of the gun cradle, the said feed sprocket being reversible on its shaft, a mounting bracket for an ammunition container, an ammunition container, and 10 means on the container for engaging the mounting bracket.

9. In combination with a machine gun having a cartridge feed opening, a feed pawl, a gun cradle structure, a cartridge feed chute mounted upon 15 said gun cradle structure and disposed in communication with said cartridge feed opening, a feed sprocket with an externally operated hand crank mounted in the said cartridge feed chute, an ammunition container supporting bracket 20 mounted on the gun cradle, an ammunition container mounted on the said bracket, an ammunition belt in said container, the ammunition container having a cartridge of its load disposed to mate with and engage the sprocket which is 25 mounted in the said feed chute, and the said sprocket and hand crank being disposed to crank the end of the ammunition belt into the feed opening of the gun and past the feed pawl of the gun so that the ammunition will feed directly into 30 the gun when the gun is charged.

10. In combination in a structure as set forth in claim 9, a guide roller mounted in the cartridge feed chute to resist the upward pull of the ammunition belt as it is fed into the gun, the said guide 35 roller being mounted to provide limited longitudinal movement thereof, so that it will permit the ammunition belt to follow the recoil motion of the gun with a minimum of friction and drag.

11. In combination with a machine gun having 40 a cartridge feed opening, a gun cradle, said gun cradle having horizontally disposed elevation trunnions, a vertically disposed support plate secured to said gun cradle at the side thereof, a cartridge feed chute mounted on said support 45 plate in communication with said cartridge feed opening and extending upwardly from said cartridge feed opening and having an inlet opening at its upper end, an ammunition container supporting bracket also mounted on said support 50 plate and disposed adjacent said feed chute, an ammunition container disposed at one side of said cradle and having an outlet opening at its upper end disposed in communication with the inlet opening of said feed chute, means removably 55 mounting said ammunition container on said supporting bracket in a substantially balanced position in respect to the center line of the elevation trunnions of the cradle, said vertically disposed support plate providing a common support for 60 said feed chute and said ammunition box and bracket, said means removably mounting said ammunition container on said supporting bracket comprising arms depending from said bracket and providing inclined surfaces, and notches in 65 the top of said bracket, and projecting members on said ammunition container providing surfaces removably engaging said inclined surfaces and notches of said bracket, and pivoted spring-pressed manually releasable latch means on said 70 bracket releasably engaging a projecting member of said container, the wall of said container adjacent said feed chute being shaped inwardly to clear portions of the feed chute assembly, the upper part of said wall of the container being bent over and providing the lower wall of said

outlet opening, and a spring pressed retaining pawl mounted in the top of said container and extending into said outlet opening to engage the cartridges.

Certificate of Correction

Patent No. 2,573,749

November 6, 1951

PHILLIP R. WHEELER ET AL.

It is hereby certified that error appears in the printed specification of the above numbered patent requiring correction as follows:

Column 7, line 59, strike out "adjacent its inlet opening" and insert the same after "chute" and before the comma in line 61;

and that the said Letters Patent should be read as corrected above, so that the same may conform to the record of the case in the Patent Office.

Signed and sealed this 4th day of March, A. D. 1952.

[SEAL]

THOMAS F. MURPHY,
Assistant Commissioner of Patents.
